GARMENT HANGER

John J. Cavanagh, Farmingdale, N. Y.

Application May 28, 1942, Serial No. 444,793

6 Claims. (Cl. 223—91)

This invention relates to garment hangers and refers more particularly to an improvement in hangers for trousers to serve as a means for effectively supporting and suspending the trousers in an inverted position from the bottom of the legs without mussing or distorting the garment or damaging or marring the fabric.

The invention broadly comprehends a hanger for trousers which is so constructed and arranged as to set up clamping and stretching forces for supporting the trousers which forces normally function jointly, but either of which alone is sufficient to sustain the weight of the trousers thereby providing a margin of safety which practically precludes any possibility of accidental or unintentional release and dropping of the garment from the hanger.

The invention also resides in the provision of an improved form of clip for clamping the trousers and novel means for anchoring the clip to the hanger bar section.

As a further feature the invention embodies a resilient supporting means for the hanger bar which is associated with the sections thereof so as to normally effect extension of the same and to tension the same against contraction.

The invention further resides in the provision of a suspension hook formed integral with the resilient supporting means or secured thereto so as to prevent shifting of the same thereon.

With the above enumerated and other objects in view, the invention is set forth in greater detail in the following specification and illustrated in the accompanying drawing, in which:

Fig. 1 is a perspective view of a combined coat and trousers hanger constructed in accordance with one form of the invention.

Fig. 2 is an enlarged vertical sectional view taken approximately on the line 2—2 of Fig. 1.

Fig. 3 is a fragmentary enlarged sectional view 40 taken approximately on the line 3—3 of Fig. 2.

Fig. 4 is a collective perspective view illustrating a portion of the hanger bar and one of the clips in separated juxtaposition.

Fig. 5 is a perspective view of a modified form of the invention illustrating a trousers hanger.

Referring to the drawing by characters of reference and particularly to the form of the invention illustrated in Fig. 1, the garment hanger is disclosed for supporting both a coat and a pair of trousers. In this form of the invention, A designates generally a longitudinally extensible and contractible hanger bar which is composed of a pair of rigid strap sections 10 and 11, the inner end portions of which are overlapped and ar-

ranged in side by side flat contact with each other.

The inner terminals 12 of the sections 10 and 11 are offset laterally and slotted at 13 so that the inner end portion of each strap section extends through the slotted terminal of the other strap section for slidably associating the sections for relative longitudinal sliding movement with reference to each other.

The outer end portion of each of the strap sections 10 and 11 which protrudes beyond the offset slotted terminal 12 of the other section, carries a clip designated generally by the reference character B, and said clips are rigidly affixed thereto for sliding movement with the strap section by which they are carried. As shown, each clip consists of a split hollow cylindrical tube 15 and a pair of clamping jaws 16, the upper reduced terminals 17 of which protrude upwardly through slots 18 formed in the tube and provide manipulating terminals adapted to be pressed together for opening the jaws against the tension of the resilient tube. The edges 19 of the split portion of the tube bear against the jaws 16 to normally move the lower extremities of the same into engagement with each other and said edges 19 engage within transverse grooves formed in the outer surfaces of the jaws to lock the jaws in assembled relation with the tube.

As illustrated, the outer end portions of the strap sections 10 and 11 are each formed with a notch 20 in the upper edge thereof, the inner end wall of which notch is formed with an undercut recess 21 providing an overhanging lip 22, while the outer end wall 23 of the notch 20 is disposed vertically. The opposite ends of each tube 15 are formed with aligned notches 24 and 25, and the spacing between the inner ends of the notches 24 and 25 corresponds approximately to the length of the notch 20 in the strap section between the end of the undercut recess and the vertical wall 23.

In assembling the clip B with its hanger bar section 10 or 11, the notched inner end 24 of the tube 15 is engaged under the overhanging lip 22 and within the undercut recess 21 so that the opposite sides of the notch 24 engage the opposite side faces of the strap section and the overhanging lip 22 extends beyond the inner end of the notch 24. The opposite sides of the notch 25 fit on opposite sides of the strap section adjacent the end wall 23 of the notch 20 and the upper portion of the end wall 23 is then peened over the notched end 25 of the tube 15 to provide a retaining lip 26. This anchors the clip B to the

strap section for movement therewith as the sections are moved longitudinally relative to each other for extension and contraction of the hanger bar A.

In the form of the invention illustrated in Fig. 1, the outer end portions of the strap sections 10 and 11 are normally moved longitudinally outward and tensioned against inward movement by means of an upwardly bowed resilient coat supporting member designated generally by the reference character C, and which member is constructed of a length of resilient wire formed to provide an intermediate upstanding coil 28 having downwardly curved oppositely directed arms 29 formed with inwardly and upwardly directed terminals 30, the laterally bent extremities 31 of which extend through apertures 32 in the outer ends of the strap sections 10 and 11 respectively. This resilient expandable supporting means C functions to extend the hanger bar A and to normally move the clips away from each other so as to stretch the leg terminals of a pair of trousers when the jaws 16 of the clips B are engaged within the leg terminals adjacent the front and rear creases. It is thus apparent that the trousers are supported by both the frictional clamping action of the jaws of the clips and the stretching force.

The intermediate upstanding coil 28 is preferably composed of three convolutions and the upper portion of the central convolution is offset upwardly as at 33 to receive therethrough a clevis 34 between the upstanding terminals of which the lower end of a suspension hook 35 is arranged and fulcrumed on a rivet 36 so that the suspension hook, when not in use, may be swung downwardly to an out-of-the-way compact position. By offsetting the central convolution of the coil 28, the emplacement of the clevis 34 is facilitated while the same is rigidly maintained in a centralized position to prevent shifting thereof.

In the form of the invention illustrated in Fig. 4 of the drawing, the hanger is designed solely for the purpose of hanging trousers and in this instance the resilient expandable supporting means, designated by the reference character D, is constructed of a single length of resilient wire bent upon itself to provide a double strand suspension hook 40, an intermediate coil 41 and a pair of downwardly and oppositely directed arms 42, the hook terminals 43 of which are engaged through transverse openings 44 in the outer end portions of the strap sections 45 and 46 which are connected together for guided slidable movement relative to each other by means of interengaging pin and slot connections 47 and 48 to provide an extensible and contractible hanger bar E.

What is claimed is:

1. In a garment hanger, a hanger bar composed of a pair of rigid linear sections connected together for guided relative longitudinal movement with reference to each other, a clip secured to the outer end portion of each section having a pair of depending spring closed clamping jaws adapted to engage within the leg terminals of a pair of trousers to clampingly support the same in an inverted hanging position, and means for suspending the hanger bar from a support consisting of a resilient element having normally expanded terminal portions secured respectively to the outer end portions of said hanger bar sections for moving the clips away from each other to stretch the leg terminals of the trousers and for tensioning the clips against movement towards each other.

2. In a garment hanger, a hanger bar composed of a pair of rigid linear sections connected together for guided relative longitudinal movement with reference to each other, a clip secured to the outer end portion of each section having a pair of depending spring closed clamping jaws adapted to engage within the leg terminals of a pair of trousers to clampingly support the same in an inverted hanging position, and an upwardly bowed resilient coat supporting member having inwardly directed opposite extremities secured respectively to the outer terminals of the hanger bar sections for tensioning the same against inward movement and for normally moving the same together with the clips away from each other for stretching the leg terminals of the trousers when supported by the clips.

3. In a garment hanger, a longitudinally extensible and contractible hanger bar composed of a pair of rigid strap sections having the inner end portions thereof arranged in flat contact, a slotted laterally offset terminal at the inner end of each strap section through which the other strap section extends, a clip secured to the outer end portion of each strap section having a pair of depending spring closed clamping jaws adapted to engage within the leg terminals of a pair of trousers to clampingly support the same in an inverted hanging position, and resilient expandable supporting means for suspending the hanger bar and secured respectively to the outer end portions of the strap sections to effect extension of the hanger bar and to tension the same against contraction so as to normally move the clips away from each other for stretching the leg terminals of the trousers.

4. In a garment hanger, a longitudinally extensible and contractible hanger bar composed of a pair of rigid strap sections having the inner end portions thereof arranged in flat contact, a slotted laterally offset terminal at the inner end of each strap section through which the other strap section extends, a clip secured to the outer end portion of each strap section having a pair of depending spring closed clamping jaws adapted to engage within the leg terminals of a pair of trousers to clampingly support the same in an inverted hanging position, an upwardly bowed resilient coat supporting member having inwardly and upwardly directed opposite extremities secured respectively to the outer end terminals of the strap sections for effecting the extension of the hanger bar to normally move the clips away from each other and to stretch the leg terminals of the trousers.

5. In a trousers hanger, a hanger bar including a pair of rigid strap sections each having a notch in the upper edge thereof formed with an undercut recess in one of its end walls, a clip carried by the outer end of each section composed of a pair of clamping jaws, and a cylindrical resilient tube split along the underside thereof to straddle the jaws and having transversely spaced slots on the upper side for respectively receiving the upper ends of the jaws so as to normally close the jaws and tension the same against relative separation, the upper portion of the tube being fitted within the strap section notch and having notched opposite ends engaging over the end walls of the strap section notch with one end of the tube fitted within the recessed end wall of the strap section notch and with a portion of the opposite end wall of the strap section notch peened over the remaining notched end of the

tube to secure the clip to the strap section for movement therewith.

6. In a hanger, a hanger bar composed of rigid linear sections connected together for guided relative longitudinal movement with reference to each other, a clip secured to the outer end portion of each section having a pair of depending spring closed clamping jaws adapted to engage within the leg terminals of a pair of trousers to clampingly support the same in an inverted hang-

10

ing position, and means for suspending the hanger bar from a support consisting of a resilient element having normally expanded terminal portions secured to the outer end portions of the hanger bar sections and having an intermediate coiled portion, the central convolution of which is provided with an upwardly offset portion and a suspension element secured to said upwardly offset portion.

JOHN J. CAVANAGH.
